UNITED STATES PATENT OFFICE.

IVAR RENNERFELT, OF HALMSTAD, SWEDEN.

ELECTRIC FURNACE.

1,076,518.

Specification of Letters Patent.

Patented Oct. 21, 1913.

Application filed February 26, 1912. Serial No. 680,003.

To all whom it may concern:

Be it known that I, IVAR RENNERFELT, a subject of the King of Sweden, and a resident of Halmstad, in the county of Halland and Kingdom of Sweden, have invented certain new and useful Improvements in Electric Furnaces, of which the following is a specification.

My invention relates to improvements in electric furnaces in which the heat is generated by means of arcs and the objects of my invention are: to provide means for changing of the vertical location of the source of heat in the interior of the furnace at the will of the operator; to afford facilities for operating the furnace with arcs independent of the charge or, if so desired, with arcs between the charge and the electrodes; to afford an easy access to the interior by arranging the electrodes and their supports so as to permit their withdrawal entirely from the openings in the walls made for the electrodes; to afford means for an automatic stirring of the molten charge; to arrange the electrodes in such a manner as to permit the operation of a furnace on any system of electric power supply, direct current or alternating current of any phase number or frequency; to facilitate smelting of cold scrap using power from small units of distribution, sensitive to disturbing influences regarding the voltage regulation; to build the smelting crucible of an electric furnace so as to obtain a considerable mechanical strength at the same time utilizing as much of the energy supplied as possible. I gain these objects by arranging the electric furnace as illustrated in the accompanying drawing in which—

Figure 1 is a vertical section of a furnace with electrodes arranged in a horizontal position as well as vertical or rather radial position. Fig. 2 is a sectional view of the furnace in Fig. 1 on the line $x-x$. Fig. 3 is a vertical, part sectional, part side view of a furnace having horizontal electrodes which may be tilted in different angles, whereas those of Figs. 1 and 2 are intended to be adjusted vertically by moving the electrodes transversely to their axis maintaining the same always parallel to its original location.

The radial electrode may be omitted in case of using direct or single phase current

but it may also be connected to the neutral wire in a 3-wire system or it may be used with single phase current taking the sum of the currents in the end electrodes. On polyphase systems, which are transformed to twophase current, if the power supply is threephase current, said radial electrode is to be connected to the middle point of the secondary of the twophase transformer and carries the geometrically resulting current of the components in the two phases. 65

Throughout the several views similar parts are indicated by similar letters of reference.

The smelting hearth of the furnace has the shape of a cylindrical crucible 1, resting on rollers 2 so as to be easily rotated for discharge of slag and metal through the spout 3.

The charge of for instance molten steel and slag is indicated by 4. A projection 5 from the lower part of the crucible serves as 75 means for stirring or mixing the charge by rotating the crucible one way or the other.

The heat is generated by means of arcs between the radial electrode 6 and more or less horizontal electrodes 7. The radial electrode is longitudinally adjustable but not otherwise. The horizontal electrodes are supported by suitable means 8 permitting the raising or lowering of the electrodes according to where the arcs are wanted in 85 the crucible. The means for said adjustment may be either a hoisting rope 9 from a trolley 10 or some other arrangement as for instance hydraulic or pneumatic lifts located on the ground. 90

The radial electrode need not be electrically insulated but is provided with cooling medium by means of a waterjacket 11. The horizontal electrodes are cooled by similar waterjackets 11 and well insulated electrically from each other and from the radial electrode. 95

Means for adjusting the length of the arcs are shown in Fig. 3 and consist of a pipe 12 insulated from the cooling jacket by 100 means of a packing 13 of asbestos or similar material. Inside of the pipe is an elastic packing of copper gauze 14 making a sliding contact with the electrode with enough frictional resistance to cause the electrode to 105 follow the movement of the pipe in or out. Said movement is caused by any approved means, such as a screw, a hydraulic plunger

or other suitable arrangements not indicated on the drawing. The current is conducted to the electrode by means of clamps 15, on the electrode or the pipe surrounding same; 5 the pipe and the packing between it and the electrode is of copper or other conducting material. The horizontal electrodes of Fig. 3 are supported on trunnions or journals 16 permitting an angular movement of the 10 electrode around an axis located at right angle to the longitudinal axis of the electrode. The electrode is protected from the furnace heat by means of a shield 17 of highly refractory material supported by the 15 trunnions 16 and moving with the electrode.

By giving the end electrodes of Fig. 1 a suitable inclination toward the charge and then lowering them close enough to the surface of the charge together with the radial 20 electrode, if such be used, it becomes possible to heat the bath directly by arcs operating on the charge itself making same part 25 of the path of the current. The same mode of operation is attained in Fig. 3 by tilting the electrodes sufficiently. It is clear that 30 this highly facilitates the operation of the furnace on cold scrap. Such a charge offers a much varying resistance to the current, if the arcs are playing on the scrap, causing bad short circuits very frequently 35 with difficulties in maintaining a smooth service. It is better, then, to use arcs independent of the charge, as long as it has not become molten and to send the current 40 through the charge, only after a bath of fluid metal and slag has been obtained. It is possible to charge more scrap into a furnace, where the electrodes may be located a proper distance above the top of the charge 45 and to maintain a minimum of distance between the arcs and the charge, as the top of this is sinking down when being smelted. In this way the highest efficiency will 50 always be maintained. The cylindrical 45 shape of the crucible not only gives to the walls and roof a high degree of mechanical strength but also serves to save energy as part of the heat which is radiated upward is reflected down to the surface of the charge. 55 Another part of the heat absorbed by the walls may be recovered by tilting the crucible so as to bring the charge into contact with the heated walls thereby absorbing some of the heat. The maintenance of a furnace of this character is relatively cheap as a new cylindrical lining may be rammed into the crucible at small cost with a minimum of time, labor and material.

Having now fully described my invention

I claim and desire to secure by Letters Patent of the United States of America:

1. In an electric furnace the combination of a crucible arranged to be rotated around a horizontal axis, electrodes projected into the crucible from opposite sides, another electrode projected vertically through the side of the crucible into close proximity to the inner ends of the first said electrodes and means for adjusting the relative distance between the three inner ends of all 70 the electrodes, the electrodes being so arranged that an arc is established from the vertical electrode to each of the other electrodes.

2. In an electric furnace the combination of a crucible arranged to be rotated around a horizontal axis, a shield at each end of the crucible, an electrode extending through each shield, another electrode extending in radial direction through the wall of the crucible, and means for adjusting the shields in vertical direction.

3. In an electric furnace the combination of a crucible arranged to be rotated around a horizontal axis, an electrode through each end of the crucible, another electrode extending vertically through the side of the crucible into close proximity to the inner ends of the first said electrodes and means for adjusting the relative distance between the three inner ends of all the electrodes, the electrodes being so arranged that an arc is established from the vertical electrode to each of the other electrodes.

4. In an electric furnace the combination of a crucible arranged to be rotated around a horizontal axis, an electrode through each end of the crucible, another electrode extending vertically through the side of the crucible into close proximity to the inner ends of the first said electrodes, means for adjusting the relative distance between the three inner ends of all the electrodes, the electrodes being so arranged that an arc is established from the vertical electrode to each of the other electrodes and means for rotating the crucible so as to vary the distance between the ends of the electrodes and the surface of the molten charge within the crucible.

Signed at Stockholm in the county of Stockholm and the Kingdom of Sweden this 30th day of January A. D. 1912.

IVAR RENNERFELT.
